UNITED STATES PATENT OFFICE.

CHARLES A. ROBBINS, OF IOWA CITY, IOWA, AND HARVEY ALLEN, OF ALLEN GROVE,
WISCONSIN.

AIR AND WATER TIGHT MAIL-BAG.

Specification of Letters Patent No. 9,253, dated September 7, 1852.

To all whom it may concern:

Be it known that we, CHAS. A. ROBBINS, of Iowa City, in the county of Johnson and State of Iowa, and HARVEY ALLEN, of Allen 5 Grove, in the county of Walworth and State of Wisconsin, have invented a new and useful Improvement in Fastenings for Mail and other Bags; and we do hereby declare that the following is a full, clear, and exact 10 description of the same, reference being had to the accompanying drawings, forming part of this specification, in which—

Figure 1, is a side view of the bag and clasp; Fig. 2, a top view representing the 15 bag open; Fig. 3, a transverse section of the jaws *a b* forming the clasp.

The same letters of reference denote same parts throughout the figures.

The nature of our invention consists in 20 securing on the outside of the bag near its mouth a clasp formed of jaws hinged together at one end and locking together at the other, the said jaws being made with a tongue and groove in them and being 25 otherwise so constructed and attached as that when closed and locked they crimp either side of the bag in between them and so form the bag itself air and water-tight.

To enable others skilled in the art to make 30 and use our invention we will proceed more fully to describe it.

A represents the bag which should be made of elastic and water proof material or otherwise be lined with the same.

35 *a b* are the metallic jaws of the clasp; they are hinged together at one end and secured by rivets or in any other way, for about half their length (more or less) from the hinge on either side of the bag near its 40 mouth.

c is the hinge uniting the jaws at their

one end, and *d* is a lock (spring or otherwise) on the opening extremity of the jaw *a*, into which lock, the hasp *e* of the jaw *b* enters for securing and locking the bag when 45 closed; the jaw *a* has a groove *f* in its interior face or side where it is attached to or presses on the bag; this groove is referred to by letter *f* in Fig. 3 and extends the whole length of the jaw; a projecting tongue 50 *g*, of similar form and length to the groove *f*, is made on the inner face of the jaw *b*, so that when the two jaws forming the clasp are brought together (in closing the bag) and locked, the elastic or flexible material 55 of the bag is crimped in between the tongue and groove of the jaws and thereby made to form a packing so as to insure, air and wa- ter tight, the mouth of the bag.

We are aware that hinged clasps or 60 clamps have been used for drawing together and keeping closed the mouth of the bag, such therefore merely of themselves we do not claim; but

What we do claim as our invention and 65 desire to secure by Letters Patent is—

Forming the jaws of the clasp with a tongue and groove on their inner faces, for crimping in the elastic material of the bag, and causing it to act as packing in effec- 70 tually making air and water tight, the mouth of the bag, as herein shown and set forth.

In testimony whereof we have hereunto signed our names before two subscribing 75 witnesses.

CHAS. A. ROBBINS.
HARVEY ALLEN.
